CLAIM

The ornamental design for an artist brush holder, as shown and described.

DESCRIPTION

FIG. 1 is a perspective view of the inner surface of the front cover of an artist brush holder showing my new design in the open position;

FIG. 2 is a perspective view of the artist brush holder of FIG. 1 showing the inner surface of the back cover and right edge thereof;

FIG. 3 is a perspective view of the artist brush holder in the closed position showing the outer surface of the front cover; and

FIG. 4 is a perspective view of FIG. 3 showing the outer surface of the back cover.

FIG. 1.

FIG. 2.

FIG. 3.

FIG. 4.
